GAME TARGET BOX

Milo W. Klingerman, 2807 W. Wyoming St.,
Indianapolis, Ind. 46221

Filed Jan. 29, 1971, Ser. No. 111,176

Term of patent 14 years

Int. Cl. D21—01

U.S. Cl. D34—5

Fig. 1.

Fig. 2.

Fig. 3.

Fig. 4.

Fig.5.

Fig.6.

Fig.7.

Fig.8.

Fig. 9.

FIG. 1 is a top plan view of a game target box in a closed position showing my new design.

FIG. 2 is a side elevation view thereof.

FIG. 3 is a bottom plan view thereof.

FIG. 4 is an end elevational view taken from either end of the box in FIG. 1.

FIG. 5 is a top plan view similar to FIG. 1, but showing the box in an open condition.

FIG. 6 is a front elevation similar to FIG. 2, but showing the box in the open condition of FIG. 5.

FIG. 7 is a bottom plan view of the box illustrated in FIG. 5.

FIG. 8 is an end elevation of the box illustrated in FIG. 5 taken from either end of the structure.

FIG. 9 is a vertical section taken along the line 9—9 of FIG. 5 in the direction of the arrows of FIG. 5.

I claim:

The ornamental design for a game target box, as shown and described.
